UNITED STATES PATENT OFFICE.

JOHN VAN VLECK, OF NEW YORK, N. Y.

DESIGN FOR A CASE FOR ELECTRICAL MEASURING-INSTRUMENTS.

SPECIFICATION forming part of Design No. 23,298, dated May 22, 1894.

Application filed April 13, 1894. Serial No. 507,476. Term of patent 14 years.

To all whom it may concern:

Be it known that I, JOHN VAN VLECK, of the city, county, and State of New York, have invented and produced a new and original Design for Cases for Electrical Measuring-Instruments, of which the following is a specification.

The accompanying drawing represents an instrument case in perspective showing my design.

The leading and characteristic feature of my design is the triangular configuration of the instrument case, the said triangle showing two straight sides and one side partly straight and partly curved. The opposite sides of the case, one of which is shown at A,

are flat and parallel. The edge or periphery of the case is of much less width than the side A. The part B of said periphery is straight. Adjacent and at an angle thereto is the straight part, E. Adjacent to the straight part E is the curved part D. Extending between the curved part D and the part B is the straight side C.

I claim—

The design for an electrical measuring instrument case substantially as herein shown and described.

JOHN VAN VLECK.
